UNITED STATES PATENT OFFICE.

CHARLES M. HECK, OF RALEIGH, NORTH CAROLINA.

MULTIPLE-RECORD-REPEATING PHONOGRAPH.

1,342,442.

Specification of Letters Patent.

Patented June 8, 1920.

Application filed May 6, 1915. Serial No. 26,335.

To all whom it may concern:

Be it known that I, CHARLES M. HECK, a citizen of the United States, residing at Raleigh, in the county of Wake and State 5 of North Carolina, have invented new and useful Improvements in Multiple-Record-Repeating Phonographs, of which the following is a specification.

This invention relates to records for sound 10 reproducing mechanisms, and to apparatus employed in making and reproducing sounds from said records.

One of the objects of the invention is to provide a record body of any of the well 15 known types, with a multiple record groove, *i. e.*, with a groove having side walls and a bottom wall, the surfaces of which walls have been treated to form independent sound records. A further object is to provide 20 a record having a groove provided with means whereby lateral and vertical motions of a stylus may be obtained from one surface. A further object is to provide a sound recording and reproducing apparatus, and 25 means coöperating therewith, to selectively make or reproduce records on the walls of said multiple record groove. A further object is to provide a sound reproducing apparatus which is capable of reproducing a 30 record irrespective of whether the same is made with a groove varying vertically as to depth, or has its sides varying laterally. A further object is to provide a sound recording and reproducing apparatus, constructed to simultaneously or selectively record 35 or reproduce, with a single groove, two or more recorded selections. A further object is to provide means whereby a groove that varies both vertically and laterally may 40 be utilized for recording and reproducing sound.

The invention will be hereinafter fully set forth and particularly pointed out in the claims.

45 In the accompanying drawings:—

Figure 1 is a diagrammatic sectional view illustrating a sound record made in accordance with the invention. Fig. 2 is a side view of a sound reproducing apparatus capable of use in connection with such a record. Fig. 3 is a plan view of a portion thereof. Fig. 4 is a detail view of the controlling device. Fig. 5 is an enlarged detail view illustrating diaphragms and styli co- 50 operating therewith, for operating both vertically and laterally. Fig. 6 is an enlarged

detail view thereof. Figs. 7 and 7^a are detail views illustrating the method of recording both types of sound vibration. Figs. 8 and 8^a show a modified form of reproducing instrument. Fig. 9 is a view of the automatic device by means of which the desired record within the record groove is selected. Figs. 10, 11 and 12 are detail views illustrating the manner in which the stylus 60 engages the record. Figs. 13, 14, 15, 16, and 17 are enlarged views of details of the reversing mechanism. Fig. 18 is a detail view of one of the tappets. Fig. 19 is a detail sectional view of the setting cam and its 65 operating arm.

Referring to the drawings, 10 designates the body of a sound record, which may be provided with a flat surface, or a convexed surface, which surface contains a groove 75 adapted to be moved with respect to a needle or stylus. Said body may be constructed of any of the well known or preferred materials. In the bottom wall 11 of said groove is formed a record 11^a produced by 80 vertical movements of a recording stylus. In the vertical wall 12 of said groove is formed a sound record 12^a, produced by a movement of a recording stylus, laterally with respect to the middle of the groove, and a similar 85 sound record 13^a is produced in the wall 13 of said groove, the result being that three independent sound records are provided in one groove, the said groove being of sufficient width and depth to permit the stylus 90 to operatively engage either record without engaging the others.

In order to make or reproduce the records above described, it is obvious that styli of different types are necessary, according to 95 the character of the sound record. In Fig. 5 is illustrated a support 15, in which is mounted the horizontal diaphragm 16, connected with a stylus lever 17, carrying a stylus 18, said lever being pivotally supported at 19, in a movable weighted member 20, providing a floating fulcrum for said lever, the construction referred to being similar to the well known hill and dale type. A vertically disposed diaphragm 21, is connected with a support 22, provided with a 105 suitable holder for a stylus or needle 23, mounted to vibrate laterally. The stylus 18 is adapted to coöperate with the record 11^a, and the stylus 23 to coöperate with the records 12^a and 13^a. The movement of the weight 20, is adjusted by an arm 24, con- 110

nected to said weight, and provided with an overhanging portion adapted to contact with one end of a lever 25, pivotally supported by a guide 26. Slidably mounted in the 5 guide 26, is a leg 27, provided at its lower end with a foot 28, adapted to rest upon the surface of the record body, said foot being preferably provided with a wheel, movable upon an axis parallel with the surface of 10 said body. The upper end of the leg 27 is provided with a threaded shank, engaged by an adjusting nut 29, said nut being also provided with a cam groove 30, engaging the end of lever 25. In operation, by ad- 15 justing the nut 29, the foot 28 pressing against the record raises or lowers 22 and with it the end of the tone arm is raised. When the end of the tone arm is raised, the stylus 23 is raised out of contact with the 20 record, and the stylus 18 only, is allowed to act. When 22 is lowered, the stylus 23 is lowered, and the cam groove 30, acting on the lever 25, lifts the arm 24 and the weight 20, thereby elevating the stylus 18. The 25 cam groove 30 is provided with a return groove, in which the end of lever 25 runs, and when lever 25 reaches the point 30^a in said return groove the leg 27 has been so adjusted as to permit both styli to engage 30 the record surface. By means of this arrangement, the weight 20 remains lowered, while 28 is also lowered and the stylus 23 engaged with the record.

In order to maintain the stylus 23 in contact with either of the records 12^a or 13^a, various means may be provided, one of 35 which is illustrated in Figs. 2, 3 and 4. Referring to said figures, the diaphragms heretofore described, communicate their vibrations to the space within a suitable tone arm or amplifying device 31, pivotally mounted upon the end of a chamber 32, and having a pivot pin 33 rigidly secured in a bracket 34, suitable sound insulating ma- 40 terial 35 being interposed between said bracket and the tone arm 31. The pivot 33 conforms to the axis of the chamber 32. The upper end of said pivot is mounted in an arm 36, supported in a suitable manner, 45 and rotatably supported in said arm is a shaft 37, provided with a gear 38, which meshes with a pinion 39, on the pivot pin 33. Secured to the pin 33 are two oppositely wound spiral springs 40, 41, said 50 springs being anchored to a depending portion 43 of the arm 36. Pivotally supported by the shaft 37, are pawls 44, normally held in engagement with teeth 45, formed in the wall of the recess 46, in arm 36, by means 55 of a suitable spring 44^a. The pawls may be disengaged from the teeth in any suitable or preferred manner. In Fig. 2, the construction designed for this purpose comprises a cap 47, normally held elevated by a 60 spring 48, said cap being carried by the 65

shaft 37, and arranged to effect disconnection of the pawls with respect to the teeth 45, when said cap is depressed. Said cap is connected with the shaft 37, so as to rotate therewith, and a suitable pointer 49 is 70 provided. By depressing the cap 47, and turning it in either direction, one or the other of the springs 40 or 41, is placed under tension, and as a consequence the spring that is wound up, tends to force the tone arm 31, 75 and the stylus coöperating therewith, to one side. When it is desired to keep the stylus in contact with the record 12^a, the pointer 49 is moved from the zero position (Fig. 4), toward the position marked "Inside 80 wall," the movement being in a clockwise direction. The effect of this is to wind the spring 40, placing sufficient tension upon the tone arm 31, to hold the stylus in contact with the wall 12. The degree of pressure upon the stylus may be varied according to the nature of the selection represented by the record, the degree of the pressure being indicated by the words "Hard" and "Soft." When it is desired to 90 retain the stylus in contact with the record 13^a, the rotation of the shaft 37, is reversed, to wind the spring 41^a. The groove in the record body, is preferably made of a width that will be just sufficient to permit the 95 stylus to coöperate with the record without contacting with the opposite wall.

In Fig. 7 is illustrated a horn subdivision by means of which records of the lateral type may be made simultaneously with a 10 record of the vertical type. The said device comprises a horn 50, which leads to a horizontal diaphragm 53, and a second horn 51, leading to the diaphragm 59, said horns being united into a single unitary structure, 10^a and separated by a partition wall 52.

In Figs. 7 and 7^a, 8 and 8^a is illustrated a single stylus, provided with means for co-operating with either diaphragm. In this form of the invention, the diaphragm 53 11^a is connected with a lever 54, pivotally supported at 55, in an arm 56, a stylus 57 being pivoted to the free end of said lever. Said stylus is also connected by an arm 58, with the vertical diaphragm 59. The connection 11^b between arm 58 and the diaphragm 59 is made by means of a link 58^a, so that the arm 58 may move parallel with the diaphragm, causing little, if any motion, to be given to the diaphragm when the stylus moves 12^a vertically. Said diaphragm may also be mounted on the arm 58, as shown in Fig. 8, as a floating weight for the vertical vibration.

The operation necessary in making a record of the character above described, depends upon the action of the machine used in recording. If the machine has no reversing mechanism for its motor, each record may be made independently, using the 13^a

vertical diaphragm for the side walls of the groove, and the horizontal diaphragm for the bottom of the groove. To make a groove on a side wall, the nature of the stylus used for recording, depends upon the incline of the wall of the groove. If the incline is slight, the stylus should have a cutting surface presented to the wall, extending above the point of contact, so that it will make a clear casting or mold. Such a stylus and surface are illustrated in Fig. 10, and in Fig. 11 is illustrated a surface having a greater incline. The groove illustrated in these figures is neither the hill and dale, nor a true Beliner type. It will be noted that the stylus clears the bottom of the groove, leaving unrecorded walls extending up a short distance from the bottom of the groove to insure the proper tracking of the stylus in the bottom of the groove. This clearance is accurately controlled by the fine pitch of the nut 29.

As a result of the invention, a compound groove may be produced, that is, a groove made by uniting two motions at right angles in a single stylus. One motion is communicated to it by the vertical diaphragm, which cuts into the side wall of the groove, and simultaneously, a horizontal diaphragm imparts a vertical motion. Fig. 12 illustrates a stylus operating in a groove, in the above manner. The point of the stylus is sharpened at an angle equal to the wall angle. The groove is illustrated as wide enough to accommodate a compound vibration in each corner. The two diaphragms, if used simultaneously, may be used simply for sound intensification and betterment, as each diaphragm may be made to suit a characteristic part—such for instance, a solo and an accompaniment—and the same simultaneously recorded by the stylus best suited thereto. Or a division of the horn may be made or two horns used, as suggested in Fig. 7, so that only one part falls on one diaphragm—*i. e.*, a surface varying in more than one plane. In any of these cases, the methods of reproduction and of recording are so similar, as to be practically the same, and the variation of apparatus to meet either function does not entail any essential difference. The terms "recording" and "reproducing" have therefore been employed herein as interchangeable.

The system hereinbefore described, is best used with a record made on one side of the groove, to be operated with the record body moving in one direction, and a record on the bottom, or other side of the groove, to be played by reverse rotation of the record body. The automatic reverse mechanism illustrated makes this possible both in recording and reproducing.

In Fig. 9 is illustrated mechanism for effecting an automatic reversal of the rotation

of the record body, when the stylus has reached the end of one of the records in the record groove. Referring to said figure, 60 designates a motor operatively connected to a drive shaft 61, provided with oppositely disposed, spaced apart bevel gears 62, 63, said shaft 61 being longitudinally movable to bring either of said gears into mesh with a pinion 64, attached to the disk shaft 65, to which the record-supporting platen 66 is attached. Secured to shaft 61 are spaced apart disks 67, 68, provided with peripheral projections 69.

Mounted to rotate between the disks 67 and 68, and at right angles to the axis of 80 said disks, is a cam shaft 70, provided with a cam 71, arranged to engage either of said disks to effect longitudinal movement of the shaft 61. Pivotedly attached to the cam shaft 70, are operating arms 72, 73, each 85 normally held in a predetermined horizontal position, by springs 74, said arms overhanging the respective disks 67 and 68, but normally clearing the projections 69. Pivoted to the frame of the machine, is a cam lever 90 75, having the cam portion 76, which is normally held elevated by means of a spring 77, bearing upon the other end of the lever. Said lever is mounted to work in a guide 78, which serves to prevent lateral movement of the lever. To the upper end of the cam shaft 70, is attached a pointer 79, located over and coöperating with a scale containing legends such as "Automatic off," "Right" and "Left." 100

Mounted in suitable bearings, is a setting shaft 80, provided with loosely attached setting members 81, 82, each of said setting members being of approximately sector shape and provided with an abutment 83. 105 Springs 84, attached to collars carried by the shaft 80, serve to normally move the abutments 83 toward each other, so as to embrace or engage either side of a depending portion 85, of an operating arm 86, attached to the base of the tone arm 87, so as to swing with said arm. The setting members are normally held against pivotal movement on the shaft 80, under the influence of springs 84, by means of clutch levers 88, pivotally supported by the shaft 80, and held in engagement with teeth 89 on the faces of said setting members, by means of springs 90. Said clutch levers are disengaged by means of tappets 91, pivoted to a tappet member 92, 110 slidingly supported in a position parallel with the shaft 80, one end of said tappet member being supported in the bracket 80^a, the other end being attached to the slide 102, hereinafter described. The tappets are 115 yieldingly held in operative position by means of springs 93. The shaft 80 is mounted to rotate in its bearings, but rotation is normally resisted by a spring 94, which spring acts to return the shaft to a 120 125 130

predetermined position when said shaft is rotated and released.

Attached to the shaft 80 is a setting cam 95, provided with a plurality of cam faces 96, arranged to engage cam lever 75, to move the latter downward against the tension of spring 77. Said setting cam is provided with an opening 97 to receive the end of a wedge-shaped arm 98 attached to the tappet member 92. Said tappet member is shifted longitudinally, by means of a depressible cam 99, pivotally supported at 100, the cam portion of said member being arranged to engage a projection 101, attached 10 to a slide 102, the tappet member being also attached to said slide. A spring 103 acts to hold the slide in such position that the finger or projection 101 will normally lie in the path of movement of the cam 99. In 15 order to maintain a tension upon the arm 86, a lever 103^a is pivotally attached thereto at one end, the free end of the said lever being provided with a roller 104, held yielding- 20 ingly against the periphery of the platen 66, by a spring 105. The advantage thus provided is substantially the same, irrespec- 25 tive of the direction of rotation of the platen 66, the direction of resistance being against the direction of motion of said 30 platen. A spring catch 105^a has a wedge shaped portion to engage the lever 103^a to hold the roller 104 out of engagement when desired.

The roller 104 is mounted to rotate with 35 more or less friction, and if desired the amount of friction may be varied in suitable manner, as by means of a nut 104^a. The spring 105 presses roller 104 against the platen 66, and the friction produced by the 40 said roller in its rotation, in contact with the platen, develops a force tending to drag the roller in the direction of motion of the platen at that point, thereby tending to impart movement to the tone arm in the same 45 direction. This is true irrespective of the direction of rotation of the platen.

In operation, a record body provided with a multiple record, such as above described, is placed in position upon the platen 66, the 50 sound box having been moved to one side, and also elevated, in the usual manner. The tone arm 87 is then brought back over the record body, and the cam key 99 is depressed. As the cam 99 engages the pro- 55 jection 101, two operations simultaneously take place. First, the tappet member 92 is moved to the left as viewed in Fig. 9, caus- 60 ing the tappets 91 to temporarily disengage clutch levers 88 from the setting members 81 and 82, whereupon said setting members will fly back against the depending portion 85 of the arm 86, under the influence of the 65 springs 84. The tappets pass beyond levers 88 so that said levers immediately reengage setting members 81 and 82, which reengage-

ment is not affected by the return movement of the tappets. Second, the setting cam 95 is engaged by the end of the arm 98, to hold the shaft 80 in its neutral position with respect to spring 94. Said spring acts to hold 70 the setting cam 95 in a normally vertical position, and this position is maintained temporarily, by the engagement of the arm 98. When the parts are positioned, as above described, the tone arm 87 is swung to the 75 farthest point at either end of the record, or to points suitably indicated upon the record body. The cam key 99 is now released, and the indicator 79 is turned to the proper indication upon the scale below it. 80 If manual operation only is desired, the pointer indicates "Automatic off," if automatic operation is desired the pointer indicates "Right" or "Left" as circumstances require. Assuming that the pointer indicates 85 "Left," as the tone arm 87 swings on its axis during the playing of the record, the engagement of setting members 81 and 82, with the arm 86, rocks the shaft 80, causing the cam 95 to move over the cam lever 75, 90 thereby depressing the cam portion of the latter, so as to force downward the operating arm 72, immediately beneath the same, against the tension of spring 77, so as to bring said arm into the path of movement 95 of the projections 69 on the disk 67. The downward movement of the cam portion 76 over the lever 72 permits the cam portion at the opposite end of lever 75 to move upwardly against the tension of the spring 77, 100 thereby permitting the lever 73 to move upwardly so as to permit the pins 69 on the disk 68 to pass beneath said lever. As soon as one of the projections 69 on the disk 67, engage the arm 72, the latter is carried 105 around with the disk, the cam portion 76 insuring that the arm remains in engagement with said projection, thereby effecting a rotation of the cam shaft 70 bringing the arms 72 and 73 into the positions shown in Fig. 14. 110 As the shaft 70 rotates the cam 71 is brought into engagement with the disk 68, thereby effecting a longitudinal movement of said shaft to disengage gear 62 from the pinion 64, and to engage gear 63 with said pinion, 115 or vice versa. When the rotation has been reversed the cam 95 is moved to a position that will permit cam portion 76; of cam lever 75, to be elevated and a corresponding cam portion 76^a, to be depressed by spring 120 77. By this means, arm 73 is forced downwardly into the path of the projections 69, on disk 68, effecting a return of cam 71, shaft 61, and pinions 62 and 63 to their original positions. In this manner rotation 125 of the platen is reversed, the stylus is caused to engage the second part of the record which is then played, the stylus being held in contact with the record in the manner heretofore fully described. When this rec- 130

ord has been played the operation automatically repeats itself, by reversing and starting again. The setting must therefore be made at the extreme point of the double record so as to include the whole, but when once set the operation is continuous as long as the motor runs.

If desired, one wall may be left blank so that the machine may for a time continue to run and the stylus continue to track without reproduction. The blank side may be used simply as a return guide for automatic repetition.

Having thus explained the nature of my invention, and described an operative manner of constructing and using the same, although without attempting to set forth all of the forms in which it may be made, or all of the forms of its use, what I claim is:—

20. 1. The combination with a body provided with a groove in its surface, said groove having a sound record on a side wall thereof, of means for moving said body, a diaphragm provided with a stylus, and means for holding said stylus selectively in engagement with either side wall of said groove.

2. As an improvement in sound recording and reproducing mechanism, a stylus, means for imparting lateral pressure thereto, and means for varying said pressure.

3. As an improvement in sound recording and reproducing mechanism, a stylus, and means for imparting lateral pressure thereto in either direction.

35. 4. As an improvement in sound recording and reproducing mechanism, a stylus, means for imparting lateral pressure thereto in either direction, and means for varying said pressure.

5. The combination with a body provided with a spiral groove in its surface, said groove having a sound record on the side walls thereof, of means for rotating said body, a diaphragm provided with a stylus, and means for holding said stylus selectively in engagement with either side wall of said groove.

6. The combination with a body provided with a spiral groove in its surface, said groove having a sound record on the side walls thereof, of means for rotating said body, a diaphragm provided with a stylus, means for holding said stylus selectively in engagement with either side wall of said groove, and means for reversing the rotation of said body.

7. The combination with a body having a groove in its surface, the bottom and side walls of said groove being respectively provided with individual sound records, of means for rotating said body, and diaphragm mechanism provided with means for selectively engaging said records.

65. 8. The combination with a body having a

groove in its surface, the bottom and side walls of said grooves being respectively provided with individual sound records, of means for rotating said body, diaphragm mechanism provided with means for selectively engaging said records, and means for reversing the rotation of said body.

9. An improvement in sound recording and reproducing apparatus, comprising a supporting member mounted to swing on a vertical axis, diaphragm mechanism carried thereby, and means coöperating with said support to exert a yielding lateral pressure thereon in either direction.

10. An improvement in sound recording and reproducing apparatus, comprising a supporting member mounted to swing on a vertical axis, diaphragm mechanism carried thereby, means coöperating with said support to exert a yielding lateral pressure thereon in either direction, and means for selectively controlling said pressure means.

11. The combination with a record support, and a tone arm mounted in operative relation thereto, of means for reversing the rotation of said record support, setting mechanism for controlling said reversing means, and means attached to the tone arm for controlling the position of said setting mechanism.

12. The combination with a record support, and means for rotating the same, of reversing mechanism, a setting cam controlling said reversing mechanism, and means for controlling the position of said setting cam.

13. The combination with a record support, and means for rotating the same, of reversing mechanism, a rock shaft, a setting cam attached to said rock shaft and controlling said reversing mechanism, and means attached to said rock shaft for controlling the position of said cam.

14. The combination with a record support, and means for rotating the same, of reversing mechanism, a rock shaft, a setting cam attached to said rock shaft and controlling said reversing mechanism, setting members connected with said rock shaft, and means for controlling the position of said setting members.

15. The combination with a record support, and means for rotating the same, of reversing mechanism, a rock shaft, a setting cam attached to said rock shaft and controlling said reversing mechanism, spring pressed setting members mounted upon said rock shaft, means for controlling the position of said setting members, and means for locking said setting members in any adjusted position.

16. The combination with a record support, and means for rotating the same, of reversing mechanism, a rock shaft, a setting cam attached to said rock shaft and con-

trolling said reversing mechanism, spring 5
pressed setting members adjustably mounted
upon said rock shaft, means for controlling
the position of said setting members, clutch
levers pivoted to said rock shaft and nor-
mally engaging said setting members, and
means for operating said levers.

17. The combination with a record sup-
port, and means for rotating the same, of
10 reversing mechanism, a rock shaft, a set-
ting cam attached to said rock shaft and
controlling said reversing mechanism, spring
pressed setting members adjustably mounted
on said rock shaft, clutch levers pivoted to
15 said rock shaft and normally engaging said
setting members, a tappet member provided
with means for disengaging said levers, and
means for actuating said tappet member.

18. The combination with a record sup-
port, and means for rotating the same, of
20 reversing mechanism, a rock shaft, a setting
cam attached to said rock shaft and con-
trolling said mechanism, setting mechanism
for controlling the position of said cam, and
25 means for preventing movement of the cam
during adjustment of the setting mecha-
nism.

19. The combination with a record sup-
port, and a tone arm mounted in operative
30 relation thereto, of means for rotating said
record support, reversing mechanism, a rock
shaft provided with means for controlling
said reversing mechanism, setting members
adjustably connected with said rock shaft,
35 and a member attached to said tone arm for
controlling the position of said setting mem-
bers.

20. The combination with a record sup-
port, and a tone arm mounted in operative
40 relation thereto, of means for rotating said
record support, reversing mechanism, a rock
shaft provided with means for controlling
said reversing mechanism, setting members
adjustably connected with said rock shaft,
45 a member attached to said tone arm for
controlling the position of said setting mem-
bers, and means for maintaining a tension
upon said tone arm member.

21. The combination with a record sup-
50 port, and a tone arm mounted in operative
relation thereto, of means for rotating said
record support, reversing mechanism, an
arm extending beneath said record support
and attached to said tone arm near its base
55 and movable therewith, and means coöperat-
ing with said arm for controlling said re-
versing mechanism.

22. The combination with a record sup-
port, and a tone arm mounted in operative
60 relation thereto, of means for rotating said
record support, reversing mechanism, an
arm extending beneath said record support
and attached to the tone arm near its base
and movable therewith, means coöperating

with said arm for controlling said reversing 65
mechanism, and means connected to the tone
arm near its base and coöperating with the
record support for maintaining a tension on
said arm.

23. In a phonograph, the combination 70
with a reproducer, and a record support pro-
vided with a drive pinion, of a drive shaft
having forward and reverse gears arranged
to selectively engage said pinion, and means
75 coöperating with the reproducer for auto-
matically shifting said drive shaft to selec-
tively engage said gears and said drive
pinion.

24. In a phonograph, the combination 80
with a reproducer, and a record support pro-
vided with a drive pinion, of a drive shaft
having forward and reverse gears, arranged
to engage said pinion, spaced apart disks
85 attached to said drive shaft, and means co-
operating with the reproducer and engag-
ing said disks to shift said drive shaft to
selectively engage said gears with said drive
pinion.

25. In a phonograph, the combination 90
with a reproducer, and a record support pro-
vided with a drive pinion, of a drive shaft
having forward and reverse gears arranged
to engage said pinion, spaced apart disks at-
95 tached to said drive shaft, a cam for en-
gaging said disks to shift said shaft, where-
by said gears are selectively engaged with
said drive pinion, and means for automatically
operating said cam.

26. In a phonograph, the combination 100
with a reproducer, and a record support pro-
vided with a drive pinion, of a drive shaft
having forward and reverse gears arranged
to engage said pinion; spaced apart disks
105 attached to said drive shaft, a cam for en-
gaging said disks to shift said shaft, where-
by said gears are selectively engaged with
said drive pinion, means for automatically
operating said cam, and means for control-
ling the position of said cam.

27. In a phonograph, the combination 110
with a reproducer, and a record support pro-
vided with a drive pinion, of a drive shaft
having forward and reverse gears arranged
to engage said pinion, spaced apart disks
115 attached to said drive shaft, and a cam shaft
provided with a cam for engaging said
disks, whereby said gears are selectively en-
gaged with said drive pinion, said cam shaft
and said disks being provided with comple-
mental means for effecting rotation of said 120
cam shaft.

28. In a phonograph, the combination
with a reproducer, and a record support pro-
vided with a drive pinion, of a drive shaft
having forward and reverse gears arranged
125 to engage said pinion, spaced apart disks
attached to said drive shaft, a cam shaft
provided with a cam for engaging said

disks, whereby said drive shaft is shifted to selectively engage said gears with said drive pinion, operating arms attached to said cam shaft, and means on said disks for engaging said operating arms.

29. In a phonograph, the combination with a reproducer, and a record support provided with a drive pinion, of a drive shaft having forward and reverse gears arranged 10 to engage said pinion, spaced apart disks attached to said shaft and provided with peripheral projections, a cam shaft provided with a cam for engaging said disks to shift said drive shaft, whereby said gears are selectively engaged with said drive pinion, operating arms attached to said cam shaft, and a cam lever for selectively depressing said operating arms into the path of movement of the projections on said disks.
30. In a phonograph, the combination with a reproducer, and a record support provided with a drive pinion, of a drive shaft having forward and reverse gears arranged to engage said pinion, spaced apart 15 disks attached to said shaft and provided with peripheral projections, a cam shaft provided with a cam for engaging said disks to shift said shaft, whereby said gears are selectively engaged with said drive pinion, operating arms attached to said cam shaft, a lever for depressing one of said arms into the path of movement of the projections on one of said disks, and means for automatically depressing said lever.
31. In a phonograph, the combination with a reproducer, and a record support provided with a drive pinion, of a drive shaft having forward and reverse gears arranged to engage said pinion, spaced apart disks 20 attached to said shaft and provided with peripheral projections, a cam shaft provided with a cam for engaging said disks to shift said shaft, whereby said gears are selectively engaged with said drive pinion, operating arms attached to said cam shaft, a lever for moving said arms selectively into the path of movement of the projections of said disks, a setting cam for operating said lever, and means for controlling said setting cam.

32. In a phonograph, the combination with a reproducer, and a record support, of means for rotating the same including reversing mechanism, a cam shaft provided 25 with means for operating said reversing mechanism, and means for automatically operating said cam shaft.

33. In a phonograph, the combination with a reproducer, and a record support, of 30 means for rotating the same including reversing mechanism, a cam shaft provided with means for operating said reversing mechanism, means for operating said cam shaft, a setting cam controlling said cam

shaft operating means, and means for controlling said setting cam.

34. The combination with a body provided with a groove in its surface, a stylus positioned to contact with a wall of said groove, and means for maintaining a lateral pressure upon the stylus to maintain the same in contact with said wall during movement of the record.

35. As an improvement in sound recording and reproducing mechanism, a record, 75 means for imparting motion thereto, a stylus, and adjustable means associated with the record moving means for automatically maintaining a lateral pressure on said stylus.

36. As an improvement in sound recording and reproducing mechanism, a record, means for moving said record in either direction, reversing means, a stylus, and means acting automatically to maintain a lateral 85 pressure on said stylus in one direction or the other according to the direction of motion of said record.

37. As an improvement in sound recording and reproducing mechanism, a record- 90 supporting spindle, a stylus, means for rotating said spindle, and means operated through rotation of said spindle to produce pressure on said stylus.

38. As an improvement in sound recording and reproducing mechanism, a rotatable mount for a sound record, a tone arm bearing a sound box having a stylus to engage said record, and a friction wheel connected with the tone arm and bearing against said 100 rotating mount for varying the operation of said stylus.

39. As an improvement in sound recording and reproducing mechanism, a stylus, a record, means for rotating said record, 105 and means coöperating with the record and operative during the rotation thereof for imparting pressure of said stylus on said record.

40. As an improvement in sound recording and reproducing mechanism, a stylus, means for imparting pressure thereto, and means for varying said pressure in either direction.

41. As an improvement in sound recording and reproducing mechanism, a rotatable sound-record mount, a stylus to engage said record, a tone arm to which said stylus is attached, and a friction wheel attached to said tone arm and pressing against said 115 rotating mount for controlling the operation of said stylus.

42. As an improvement in sound recording and reproducing mechanism, a rotatable mount for a sound record, a stylus to engage said record, a tone arm to which said stylus is attached, a friction wheel attached 125 to said tone arm and pressing against said

rotating mount, and means for maintaining said wheel in disengaged position.

43. A sound record comprising a body having its surface provided with a spiral groove, one side of which is recorded as a closing spiral, the other side being recorded as an opening spiral, and means for playing one side after another automatically.

44. The combination with a record body 10 having a groove in its surface, said groove having a sound record on the opposite side walls thereof, of means for rotating said body, means for reversing the direction of said rotation at adjustable points, a diaphragm provided with a stylus, and means for holding said stylus selectively in engagement with either side wall of said groove.

45. The combination with a record body 20 having a groove in its surface, said groove having a sound record on the opposite side walls thereof, of means for rotating said body, a diaphragm provided with a stylus, and means for holding said stylus selectively in engagement with either side wall of said 25 groove.

46. As an improvement in sound recording and reproducing mechanism, a stylus, a sound record having a groove of greater width than said stylus and provided with 30 different sound records on the walls thereof,

and means whereby said stylus is shifted to selectively engage either wall of said groove.

47. As an improvement in sound recording and reproducing mechanism, two continuously spaced apart record surfaces, a stylus, and automatic means whereby said stylus may selectively engage either record surface.

48. As an improvement in sound recording and reproducing mechanism, a stylus, a body having a record groove to engage said stylus, a sound record on a wall of said groove, and means whereby said stylus may track in said groove without engaging said 45 sound record.

49. As an improvement in a sound recording and reproducing mechanism, a moving surface, a groove therein containing a sound record on a wall thereof, a stylus to engage 50 said groove, and means whereby said stylus may track within said groove without engaging said sound record.

In testimony whereof I have hereunto set my hand in presence of two subscribing 55 witnesses.

CHARLES M. HECK.
